ABSTRACT OF THE DISCLOSURE

Cloth seams are bonded together by soaking a solid-phase, liquid-dispersed bonding agent into the seam and then coagulating the solid-phase. Coagulation may be accelerated by an acidic coagulating agent. In one embodiment of the invention, a cartridge carries a bonding agent having a basic pH in one chamber and an acidic coagulating agent in another chamber. The cartridge is removably mounted on a cartridge reciprocating crank in a sewing machine having a base plate and a presser foot which feeds the seam across the plate under the reciprocating cartridge. The presser foot is carried by a crank and a special pivot arrangement which causes the feeding-end of the foot to move in a cloth-feeding path. In a second embodiment, a hand-held instrument reciprocates a pair of cartridges into engagement with the cloth.

BACKGROUND OF THE INVENTION

The background of the invention will be set forth in two parts.

Field of the Invention

The present invention pertains generally to the field of sewing and more particularly to a sewing machine toy.

Description of the Prior Art

The prior art known to applicants is listed by way of illustration, but not of limitation, in separate communications to the U.S. Patent Office.

Additionally, toy sewing machines of the type which reciprocate a thread-carrying needle through two or more layers of material to be joined together are old and well known. It is also known that toy sewing machines of this type may be dangerous to young, inexperienced children.

OBJECTS AND SUMMARY OF THE INVENTION

It is the primary object of the present invention to provide a new and useful sewing machine toy employing a liquid-dispensing cartridge for dispensing a bonding agent onto seams for bonding two or more pieces of material together in an economical, safe and expeditious manner.

In a first embodiment of the invention, the bonding material may be provided in a cartridge removably mounted in a toy sewing machine above a supporting base plate across which the material to be sewn may be moved by a presser foot. The sewing machine reciprocates the cartridge into engagement with the garment seam simultaneously dispensing the bonding agent and a coagulating agent. The bonding agent soaks through the pores in the garment and is then coagulated so that flexible threads go through the fibers of the garment and bind the two adjoining faces together.

In a second embodiment of the invention, a hand-held instrument reciprocates a pair of cartridges into engagement with the garment.

The features of the present invention which are believed to be novel are set forth with particularity in the appended claims. The present invention, both as to its organization and manner of operation, together with further

2

objects and advantages thereof, may best be understood by reference to the following description, taken in connection with the accompanying drawings in which like reference characters refer to like elements in the several views.

BRIEF DESCRIPTION OF THE DRAWINGS

FIG. 1 is a side elevational view, with parts broken away to show internal construction, of a sewing machine toy constituting a first embodiment of the present invention;

FIG. 2 is an enlarged, cross-sectional view taken along line 2—2 of FIG. 1;

FIG. 3 is an enlarged cross-sectional view taken along line 3—3 of FIG. 1;

FIG. 4 is a view similar to FIG. 3 showing the sewing machine switch in an "off" position;

FIG. 5 is a somewhat schematic view showing the drive mechanism of the toy of FIG. 1 in different operating positions;

FIG. 6 is an enlarged, cross-sectional view taken along line 6—6 of FIG. 1;

FIGS. 7 and 8 are enlarged, end-elevational views of the machine of FIG. 1 showing certain parts thereof in different operating positions;

FIG. 9 is an enlarged cross-sectional view taken along line 9—9 of FIG. 7 showing the dispensing cartridge of the toy of FIG. 1 in a first operating position;

FIG. 10 is a view similar to FIG. 9 showing the cartridge in a second operating position;

FIG. 11 is a reduced, side-elevational view, with parts removed to show internal construction, of the cartridge shown in FIGS. 9 and 10;

FIGS. 12, 13, 14 and 15 are schematic views showing the use of a template to lay out a garment to be sewn on the sewing machine toy of the present invention;

FIG. 16 is a cross-sectional view of a sewing machine toy constituting a second embodiment of the present invention;

FIG. 17 is an end view of FIG. 16; and

FIG. 18 is a top plan view of FIG. 16, with parts broken away to show internal construction.

DESCRIPTION OF THE PREFERRED EMBODIMENTS

Referring again to the drawings, and more particularly to FIGS. 1 and 2, a sewing machine toy constituting a first embodiment of the present invention, generally designated 10, includes a housing 12 having a rear housing half 14 and a front housing half 16 each including a bottom wall 18, a top wall 20, a front wall 22 and a rear wall 24. A boss 26 may be formed on front wall 22 when housing 12 is made from a suitable polymeric material during an injection-molding operation. Housing half 14 may be connected to housing half 16 by providing a series of bosses 28 on housing half 16 and engaging them in corresponding sockets 30, which are provided on housing half 14. Housing 12 is shaped somewhat like a conventional sewing machine including an upstanding post 32 which carries a horizontal sewing-machine head 34 which is spaced above a plate 36. Plate 36 is reinforced by vertical partitions 36A, 36B and 36C extending from plate 36 to bottom wall 18.

Sewing machine toy 10 is powered by a small electric motor 38 receiving current from a pair of dry wells 40, 42 supported in a battery compartment 44 by a battery-compartment door 46 swingably connected to housing 12 by a pivot pin 48 and retained in the closed position shown in FIG. 1 by a latch mechanism 50. Motor 38 includes an output shaft 52 to which an output pinion 54 is keyed for imparting rotation to an idler gear 56 rotatably mounted in housing 12 on a shaft 58. Idler gear 56 carries

a pinion gear 60 drivingly engaging a gear 62 keyed to a crank shaft 64 rotatably mounted in housing 12 in bearings 66, 70 and 72.

Shaft 64 includes a first end 74 which carries a bifurcated tang 76 which frictionally engages a hub 78 carried by a simulated fly wheel 80 rotatably mounted on housing boss 26. Crank shaft 64 also includes a second end 82 having offset journals 84, 86 and 88 operatively associated with a presser foot assembly 90, end wall 24 and a liquid-dispensing cartridge 92, respectively.

Referring now to FIGS. 1-5, end wall 24 (FIGS. 3 and 4) is provided with a vertical slot 94 which prevents lateral movement of journal 86 while permitting vertical movement thereof. A control lever assembly 96 is reciprocably mounted in slot 94 and includes a pair of ribs 98, 100 slideably received within slot 94 and retained in position therein by clips 102, 104, respectively, disposed on the downstream side of wall 24 and by a C-shaped end 106 of lever assembly 96 disposed on the upstream side of wall 24. The other end 108 (FIG. 4) extends through a slot 110, which is provided in front wall 16, and terminates in a grip portion 112, which may be grasped by a child-user of sewing machine toy 10 for moving lever assembly 96 from the elevated position shown in FIG. 4 to the lowered position shown in FIG. 3. Lever assembly 96 may be locked in its FIG. 4 position by engaging end 108 with a shoulder 114 formed on the upper end of a locking tab 116 carried by the upstream side of wall 24.

The C-shaped end 106 of lever assembly 96 includes a lower leg 118 and an upper leg 120. Leg 118 carries a U-shaped bracket 122 caging a first offset finger 124 on a switch-actuating crank 126 rotatably mounted in housing 12 between a pair of horizontal ribs 128, 130 (FIG. 1) and the bottom wall portion 132 of arm 34. Switch-actuating crank 126 includes a second offset finger 134 adapted to engage and lift a movable electric contact 136 moving it from the position shown in FIG. 2 to the position shown in FIG. 4 when finger 134 is swung in the direction of arrow 138 (FIG. 2) by moving lever assembly 96 from its FIG. 3 position to its FIG. 4 position. This removes end 140 of contact 136 from engagement with a battery 40 interrupting the electrical circuit to motor 38. Upper leg 120 of lever assembly 96 carries a post 142 about which the body portion 144 of a torsion spring 146 is wound. Spring 146 includes a first leg 148 (FIGS. 3 and 4) having a hooked portion 150 engaged under a bracket 152 provided on wall 14 of housing 12 and a leg 154 having a curved end 156 engaged under a clip 158 carried by upper leg 120. Spring 146 biases lever assembly 96 downwardly to its FIG. 3 position and maintains the lower end 160 of rib 98 in engagement with crank journal 86 for maintaining end 82 of crank shaft 64 at a proper elevation when lever assembly 96 is in its FIG. 3 position. End 82 of shaft 64 may then be raised to its FIG. 4 position by the engagement of leg 118 and a clip 162, which is provided on the upper end 164 of rib 100, with circular discs 166, 168, respectively, carried by shaft 64 and disposed on the upstream and downstream sides of wall 24, respectively.

The electrical circuit to motor 38 will now be described in connection with FIGS. 1 and 2. A buss bar 170 is connected to battery door 46 by a rivet 172 and includes a first end 174 having a contact 176 engaging battery 40 and a second end 178 having a contact 180 engaging one end of battery 42. The other end of battery 42 is engaged by a first end 181 of a fixed contact 182 having a second end 184 staked to wall 14 by a rivet 186 which also maintains electrical communication between a first motor lead 188 and contact 182. Movable contact 136 is also staked to wall 14 by a suitable rivet (not shown) which also establishes electrical communication between a second motor lead 190 and contact 136.

Referring now to FIGS. 1, 3 and 4, the appearance of housing 12 may be enhanced by providing it with a simu-

lated control knob 192 and simulated ventilation louvres 194 formed integrally with walls 16 and 14, respectively.

Referring now to FIGS. 1, 6 and 7-10, liquid dispensing cartridge 92 includes a housing 196 having an encompassing side wall 198 (FIGS. 9-11), an open top 200 and an open bottom 202. A vertical partition 204 divides housing 196 into an acid-storage chamber 206 and a bonding-agent-storage chamber 208 communicating with open bottom 202 through outlet ports 210, 212, respectively. Open bottom 202 is closed by a nozzle assembly 214 having a flanged top portion 216, (FIGS. 9 and 10) engaged in open top 202. Nozzle assembly 214 includes a pair of discharge nozzles 218, 220 having outlet ports 222, 224, respectively, forming annular valve seats 226, 228 upon which check valves 230, 232, respectively, normally seat under the influence of compression springs 234, 236 which encompass valve stems 238, 240 which, in turn, are reciprocably mounted in hollow bosses 242, 244 provided on a horizontal partition 246 in which outlet ports 210, 212 are provided. Springs 238, 240 each includes an upper end 248 bearing against partition 246 and a lower end 250 bearing against an annular shoulder 252 provided on an associated one of the valves 230, 232. Nozzle assembly 214 is provided with a stop member 254 engageable with a work piece 256 as it travels along base plate 36 in the direction of arrow 258, to control the amount valves 230, 232 open when they bottom-out on work piece 256, and to tamp work piece 256 so that the bonding composition will soak through it faster.

Cartridge 92 includes a cover 258 (FIGS. 6 and 11) having a first portion 260 covering chamber 206 and a second portion 262 covering chamber 208 (FIG. 11). The portion 262 which covers chamber 208 is provided with an air vent 264 and a depending skirt 266 which encompasses vent 264. A flexible air sack 268 may be attached to skirt 266 for receiving air through vent 264 for equalizing the pressure which exists outside cartridge 92 and a bonding agent 270, which is stored in chamber 208. A suitable acid may be stored in chamber 206 for coagulating the bonding agent after it has been dispensed through valve 230. Air for pressurizing chamber 206 is drawn in through valve 232 each time it is unseated. In practice, it was found to be impractical to pressurize chamber 208 by drawing air in through valve 230 because freshly-dispensed acid was also sometimes drawn into chamber 208 through valve 230 causing the bonding agent 270 to coagulate and plug-up valve 230.

Referring now more in particular to FIGS. 1 and 6, cartridge 92 is mounted in a cartridge-receiving chamber 272 formed by wall 24 and a cover member 274, which is retained in position on housing 12 by a peripheral flange 276 and a hollow boss 278 which, in turn, engages a pin 280 carried by wall 24. Chamber 272 may be closed by a door 282 swingably connected to wall 24 and cover member 274 by suitable pins, like the one shown at 284 for the cover member 274. Cartridge 92 is reciprocated within chamber 272 by crank 88 which works within a slot 286 formed by upper and lower horizontal ribs 288, 290, respectively, carried by cartridge 92. Cartridge 92 also carries a pair of upper front and rear pins 292, 294, respectively, a pair of front, lower pins 296, 298 and a pair of rear, lower pins 300, 302 (FIG. 5) which properly locate cartridge 92 within chamber 272 and guide it during reciprocation thereof by crank 88. Pin 294 rides in a slot 304 formed by a pair of vertical ribs 306, 308 carried by cover member 274; pin 302 rides in a slot 310 provided by a pair of vertical ribs 312, 314 carried by cover member 274; pin 292 is prevented from moving in a lateral direction toward front wall 16 by a vertical rib 316 carried by wall 24; pin 296 is prevented from moving laterally in the direction of front wall 16 by a vertical rib 318 carried by wall 24; and pin 298 is prevented from moving laterally in the direction of rear wall 14 by a vertical rib 320 carried by cover member 274. Ribs 306 and 312 are joined together by a horizontal

rib 322 and vertical ribs 312, 318, are provided with openings 324, 326, respectively, so that pin 294 may ride along rib 322 while pins 302, 296 pass through openings 324, 326 and pin 292 passes over the upper edge 328 of rib 316 during the positioning of cartridge 92 in chamber 272.

Cartridge 92 may be swung to the position shown in broken lines in FIG. 6 when it is desired to service valves 230, 232 by moving pin 298 along a horizontal rib 330, which is provided on cover member 274, until pin 298 engages vertical rib 314.

Referring now to FIGS. 1, 3, 5, 7 and 8, presser foot assembly 90 includes a lower end 336 which carries a pair of arcuate feet 338, 340 each having a serrated edge 342 mounted directly above an associated one of a pair of rollers 344, 346 rotatably mounted in housing 12 on a shaft 348 journaled in vertical partitions 36A, 36B. An intermediate portion 350 of presser foot assembly 90 (FIGS. 1, 7 and 8) is prevented from moving laterally by housing member 34 so that crank journal 84 will cause feet portions 338, 340 to travel the path defined by arrows 352 in FIG. 5 when crank 84 rotates in the direction of arrow 354. If control lever assembly 96 is then lowered to lower end 82 of crank shaft 64, feet 338, 340 will press work piece 256 against rollers 344, 346 and move the work piece 256 in the direction of arrow 258.

Referring now to FIGS. 12-15, work piece 256 may comprise first and second plies 354, 356 of a suitable cloth material upon which a cardboard template 358 may be placed. Template 358 includes suitable elongated openings 360 through which a pencil 361 may be inserted to trace the location of areas 360A (FIG. 13) to receive the bonding agent 270 and the acid material from cartridge 92. Template 358 may also be used to trace a pattern 362 (FIG. 13) onto work piece 256. Work piece 256 may then be placed on plate 36 and rollers 344, 346 beneath feet 338, 340 which may be lowered into engagement therewith by releasing lever assembly 96. This also energizes motor 38 causing cartridge 92 and presser foot 90 to reciprocate in such a manner that cartridge 92 is traveling downwardly, as indicated by arrow 364 in FIG. 8, while feet 338, 340 are traveling upwardly, as indicated by arrow 366. Each time feet 338, 340 reach the lowermost position of their stroke, as shown in FIG. 7, they move work piece 256 in the direction of arrow 258, as indicated schematically in FIG. 5. Each time valves 230, 232 reach the bottom of their stroke, as shown in FIG. 10, they deposit drops of bonding agent 270 and the acid contained in chamber 206 to form a line of bonding composition 368 to bond the plies of 354, 356 together along the areas 361. The acid coagulates the bonding agent 270 causing rubbery, stringy fibers to entangle themselves in which the fibers of plies 254, 256 firmly bonding them together. Pattern 362 may then be cut from work piece 256 and turned inside out to hide the seams formed by the bonding composition 368.

The bonding agent 270 may comprise any suitable latex wherein a solid, rubbery phase is dispersed in water to form an emulsion having a pH of about 10-11 to prevent the solids from coagulating. A suitable acid, such as citric acid, may then be used in chamber 206 to coagulate the solids as soon as they are dispensed from chamber 208 onto work piece 256 so that rubber stringers are formed when the latex is coagulated by the acid and these stringers go through the fibers and wrap around them to bond plies 254 and 256 together. A typical formulation for the bonding agent 270 is 100 parts by weight of natural rubber latex, 2 parts by weight of an anti-oxidant, such as a modified phenol and 0.2 parts by weight of a fungistat, such as potassium sorbate. A typical formulation for the coagulant is 100 parts by weight of water, 5 parts by weight of citric acid and 0.5 parts by weight of a suitable fungistat.

In practicing the present invention, plies 354 and 356 of suitable material, such as cloth, may be placed to-

gether as shown in FIG. 12 and template 358 may be placed thereon. Pencil 361 may then be used to trace the pattern as shown in FIG. 13 at 352 and to identify the area 360A which should receive the bonding material. Work piece 256 may then be placed on plate 36 beneath feet 338, 340 (FIGS. 7 and 8) and lever assembly 96 may be released from latch 116 (FIG. 4) so that spring 146 will move the end 82 of shaft 64 downwardly to the position indicated by center line 370 in FIG. 5. Assuming that the shaft 64 was previously rotated to the position shown in FIG. 5, the center line of crank 84, which carries presser foot assembly 90, will be at the elevation indicated by center line 372 and crank 88 for cartridge 92 will be at the position indicated by center line 374.

The lowering of lever 96 swings switch crank 126 to the position shown in FIG. 2 lowering movable contact 136 to a closed position so that motor 38 is energized. Shaft 64 then rotates in a counterclockwise direction, as indicated by arrow 376 in FIG. 5, causing presser foot crank 84 to reach the lowermost point of its travel and start upwardly while cartridge 92 starts downwardly during rotation of shaft 64 about a center of rotation defined by line 378.

Each time stop member 254 (FIG. 10) bottoms out on work piece 256, valves 230, 232 will open sufficiently to discharge a drop or globule of bonding composition 368. Work piece 256 is guided over rollers 344, 346 until all areas 360A are covered with bonding composition 368. Lever assembly 96 may then be elevated and engaged on latch 116. Work piece 256 may then be removed from plate 36 and pattern 362 may be cut out from work piece 256 and turned inside out to provide a finished article, as indicated at 362A in FIG. 15.

Referring now to FIGS. 16-18, a sewing machine toy constituting a second embodiment of the present invention, generally designated 380, includes a hollow, cylindrical housing member 382 having a first threaded end 384 and a second threaded end 386 threadedly engaging a sewing machine head 388 and a battery cap 390, respectively.

An electric motor and a pair of dry cells 394, 396 are mounted in housing member 382 and are electrically connected together by suitable contacts 389, 400. Battery cap 390 carries an electrical contact 402 engageable with contact 400 for completing a circuit to motor 392 when cap 390 is tightened onto housing member 382. Conversely, the circuit may be broken by loosening battery cap 390.

Motor 392 includes an output shaft 404 which carries a pinion gear 406 drivingly engaging a reduction gear 408 keyed to a crank shaft 410 rotatably mounted in sewing machine head 388. Crank shaft 410 carries a crank 412 which engages a crank slot 414 provided in a cartridge-carrying head 416 reciprocably mounted on sewing machine head 388 by a pair of flanges 418, 420 slideably machine head 388. Cartridge-carrying head 416 may be engaging ways 422, 424, respectively, provided in sewing made in two pieces, 426, 428 which may be adhesively connected together. A pair of cylindrical bores 430, 432 are provided in cartridge-carrying head 416 for receiving a coagulant dispenser 434 and a latex dispenser 436, respectively, which may be retained in position in head 416 by a pair of protuberances 438, 440 which engage annular grooves 442, 444 provided in cartridges 434, 436, respectively.

Sewing machine toy 380 also includes a presser foot 446 which may be connected to sewing machine head 388 by suitable screws, like the ones shown at 448. Presser foot 446 includes a bifurcated end 450 through which the tips 452 of cartridges 434, 436 may be reciprocated so that valves 454, which are provided on cartridges 434, 436 and which may be identical to the valves previously described in connection with the first embodiment, will engage a suitable work piece 456 and open to deposit latex and coagulant thereon when sewing

machine toy 380 is held by a child-user and moved along work piece 456 while motor 392 is energized.

While the particular sewing machine toys herein shown and described in detail are fully capable of attaining the objects and providing the advantages hereinbefore stated, it is to be understood that they are merely illustrative of the presently preferred embodiments of the invention and that no limitations are intended to the details of construction or design herein shown other than as defined in the appended claims, which form a part of this disclosure. Whenever the term "means" is employed in these claims, this term is to be interpreted as defining the corresponding structure illustrated and described in this specification or the equivalent of the same.

What is claimed is:

1. A sewing machine toy, comprising:
a cartridge for dispensing a bonding agent; and
means for reciprocating said cartridge into engagement
with a work piece, said cartridge including:
a first chamber for containing an acid;
a second chamber for containing a latex-type bond-
ing material;
a cover for said chambers, said cover including a
portion covering said latex-containing chamber,
said portion of said chamber containing an air
vent and a depending skirt encompassing said
air vent and extending into said latex-containing
chamber;
an air sack connected to said depending skirt in
fluid communication with said air vent, said air
sack extending into said latex-containing chamber;
a first valve communicating with said acid-containing
chamber for controlling the flow of acid
therefrom;
a second valve communicating with said latex-con-
taining chamber for controlling the flow of latex
therefrom; and
a stop member depending from said cartridge adjacent
said valves, said stop member being engageable
with said work piece on said base member
to control the amount said valves open.
2. A sewing machine toy, comprising:
a housing assembly including a work piece-supporting
plate;
a flexible crank shaft rotatably mounted in said hous-
ing assembly, said crank shaft having a first end carry-
ing an input gear and a second end provided with
first, second and third cranks;
a liquid dispensing cartridge reciprocably mounted in
said housing and including means connecting said
cartridge to said first crank;
means journaling said second crank in a vertical slot
in said housing;
an operating lever assembly slideably mounted in said
vertical slot in engagement with said second crank,

said operating lever being biased downwardly in said slot to normally position said second end of said crank shaft at a proper operating elevation within said housing;
a presser foot assembly rotatably connected to said crank; and
motor means operatively connected to said input gear
for rotating said crank shaft.

3. A sewing machine toy as stated in Claim 2 wherein
said motor means is an electric motor and wherein said
toy includes a movable contact for closing an electrical
circuit to said motor, said toy including a switch crank
having a first end connected to said operating lever and a
second end engageable with said movable contact for
opening said movable contact when said operating lever
is lifted against said bias.

4. A sewing machine toy as stated in Claim 2 wherein
said cartridge comprises:

a first chamber for containing an acid;
a second chamber for containing a latex-type bonding
material;
a cover for said chamber, said cover including a por-
tion covering said latex-containing chamber, said
portion of said chamber containing an air vent and a
depending skirt encompassing said air vent and ex-
tending into said latex-containing chamber;
an air sack connected to said depending skirt in fluid
communication with said air vent, said air sack ex-
tending into said latex-containing chamber;
a first valve communicating with said acid-containing
chamber for controlling the flow of acid therefrom;
a second valve communicating with said latex-con-
taining chamber for controlling the flow of latex there-
from; and
a stop member depending from said cartridge adjacent
said valves, said stop member being engageable with
said plate to control the amount said valves open.

5. A sewing machine toy as stated in Claim 2 wherein
said presser foot assembly includes a pair of serrated
arcuate feet and wherein said sewing machine toy includes
a roller rotatably mounted in said housing beneath each
arcuate foot for minimizing frictional drag of material
being fed through said sewing machine toy by said presser
foot assembly.
